UNITED STATES PATENT OFFICE.

AUGUST WINNER, OF CHICAGO, ILLINOIS.

CASE HOLDER FOR BOOKS.

Application filed April 17, 1926. Serial No. 102,621.

This invention relates to a portable case designed primarily for the accommodation of books, there being combined with the case certain features which adapt it to function 5 as a holder for the books at the time of their use.

In the present device I have aimed to provide a case which is commodious, compact and light, and hence easily portable; a case 10 in which books are retained in such relation that when it is opened the books themselves are disposed ready for use; a case in which the books may be held in a closely grouped arrangement convenient for inter-reference 15 purposes; and a case wherein the mountings for two of the books may be shifted to different positions, as desired. The invention consists further in numerous other features of construction and combinations of parts, 20 as will more fully hereinafter appear.

A suggestive embodiment of my invention is illustrated in the accompanying drawings wherein—

Figure 1 is a plan view of the case holder 25 opened up to expose three books therein each of which is closed;

Fig. 2 is a transverse section on line 2—2 of Fig. 1;

Fig. 3 which is a view similar to Fig. 2 30 shows the mountings for two of the books transposed to different positions;

Fig. 4 is a sectional detail of one of the mountings taken on line 4—4 of Fig. 1; and

Fig. 5 is a transverse section through the 35 case holder as it appears when closed.

As shown in the drawings, the case holder comprises two companion box sections A and B, preferably rather shallow after the manner of trays, and swingingly connected together as at 6. Each section is formed of 40 corresponding parts including a bottom 7 adjacent side walls 8, and other side walls 9 which are remotely disposed when the case is opened up for use. Between the side walls 45 are extended end walls 10.

Each box section is designed for the accommodation of one book. The mountings therefor which are substantially alike each 50 include a supporting board 11 flexibly connected along one edge to an elevation board 12 which in turn is similarly joined to a base board 13 which is fixedly secured adjacent a tray bottom 7. Between the two supporting boards is extended a flexible connection 14 55 which may carry a snap fastener 15 in position to rest upon the upper edge of the adja-

cent side walls 8 when the parts are related as in Fig. 2. A laterally extending tab 15^a secured in place by this fastener may also be provided to facilitate manipulation of the 60 supporting boards. A socket member 16 designed for co-operation with the fastener 15 is provided adjacent the free edge of one supporting board 11 and serves additionally to connect therewith a flap or tab 17. By the 65 means described the supporting board may be sustained in an elevated position, as shown in Fig. 2. This movement from a down to an up position requires that each elevation board swing around through an arc of nearly 90°. In the down position one elevation board is disposed against the tray bottom 7 in alignment with its associated base board 13, and upon both of these boards the supporting board 11 is rested, thus assuming the 70 most compact relationship which is possible. The shift in positions of the supporting boards involves a sliding of the flexible connection 14 over the upper edges of the two adjacent side walls 8. By pushing down 80 upon one book the other can be raised so that the operation of reversing the book positions is very easily effected.

A flap 18 is associated with each supporting board. As shown, its two ends are joined 85 to the board ends, and in the intervening space may be accommodated one cover 19 of either book X or Y of which one is carried in each tray section. In this manner the two books are held in place whether closed or 90 opened for use. If the book X be opened out its free cover will rest upon the book Y which occupies a down position (see Fig. 3). Likewise if the positions of the books be reversed, then the free cover of book Y, when 95 opened out for use, may rest upon book X which is in the down position as shown in Fig. 2.

With a case-holder of the present construction I may also associate a third book Z together with a mounting therefor. As shown, this comprises a supporting board 20 having joined thereto a cover retaining flap 21, also a semirigid extension flap 22 which may be equipped with a snap fastener 23 for detachable connection with one end 10 of the tray structure. The upper edge of this tray end may be beveled at 24 to furnish a rest for the rear side of the extension flap whereby the book support tends to remain in a nearly 105 upright position.

The open or reading positions of the three

books have already been indicated in the preceding description. The eye may readily pass from one to another for convenient inter-reference work whenever desired. It is contemplated, however, that the present holder shall expose for reading at one time but one of the two books X or Y. The other book will then remain closed with its support in folded or collapsed condition. A reversal in the position of the supports may be quickly effected, whenever desired, thereby bringing the other book up to a reading position.

At times the case holder may desirably be closed up for greater convenience in carrying. 15 This requires merely the collapse of the book supports within the two trays, folding down of the remaining support, closing of the two tray sections upon each other as shown in Fig. 5, and snapping of a tabbed fastener 25 to 20 lock the case against opening. A strap handle 26 may also be provided, as shown.

A case holder having the characteristics noted may conveniently be made from binder board or other light material covered with 25 suitable cloth or fabric. The flexible connections required may be formed from the same fabric covering. The resulting structure is accordingly light, compact, and easily handled. For reasons such as these the case 30 holder of my invention is admirably adapted to fulfill the requirements of its intended use, it being obvious, however, that certain changes or modifications of an inconsequential nature might well be made without sacrifice of the improved features claimed herein. 35

I claim:

1. In a case holder, the combination of a 40 pair of hinged trays having marginal walls and adapted, when folded together, to provide a case, a movable book support in each tray, each support comprising a plurality of flexibly connected boards one of which is

equipped with a flap for holding the cover of a book, and a flexible means extending loosely over adjacent walls of the trays for 45 connection with the two supports, substantially as described.

2. In a case holder, the combination of a pair of adjacent trays, a movable book support in each tray, a flexible connection extending from one support to the other over the wall intervening between the two trays, and having a length sufficient to permit each support to rest adjacent its associated tray bottom, and means for detachably securing one support to the flexible connection at a point intermediate of its fixed attachment with the supports, substantially as described. 50

3. In a case holder, the combination of a pair of hinged trays adapted, when folded together, to provide a case, a movable book support in each tray, rigid means hingedly connecting the remote ends of the two supports with a point adjacent the tray bottoms, flexible means connected to the adjacent ends 60 of the two supports and passing slidably over the wall intervening between the two trays, and means whereby one support may be detachably secured to said flexible means at a point intermediate of its two fixed connections, substantially as described. 65

4. In a case holder, the combination of a pair of adjacent trays divided by a wall, a book support movably mounted in each tray, flexible means passing over the wall to connect fixedly with each support, a snap fastener carried by said means at a point adjacent the wall top when one support is in a down position, and a device carried by the other support for co-operating with said fastener whereby to sustain the latter support in an elevated position, substantially as described. 75

AUGUST WINNER.
